Primary Examiner — Janice Hallmark(57) **CLAIM**

The ornamental design for a telephone holder with a lanyard, as shown and described.

DESCRIPTION

1. Telephone holder with a lanyard

1.1 : Perspective

1.2 : Front

1.3 : Back

1.4 : Right

1.5 : Left

1.6 : Perspective

Reproduction 1.1 is a perspective view of the telephone holder with a lanyard; reproduction 1.2 is a front view thereof; reproduction 1.3 is a back view thereof; reproduction 1.4 is a right side view thereof; reproduction 1.5 is a left side view thereof; reproduction 1.6 is a perspective view of the telephone holder with a lanyard.

1 Claim, 6 Drawing Sheets(56)
